ARTICLE FEEDING MECHANISM

Harry Peters, Middletown, Ohio, assignor to The
Raymond Bag Company, Middletown, Ohio, a
corporation of Ohio

Application December 11, 1951, Serial No. 260,981

16 Claims. (Cl. 271—41)

1

This invention relates to a machine for automatically feeding articles from a stack of said articles and is designed more particularly for feeding flat bag tubes from the bottom of a stack of such tubes to a mechanism which is to complete the construction of the bag.

One object of the invention is to provide a machine which will withdraw the lowermost article from the stack of articles and advance the same to a point of delivery.

In the manufacture of multiply sewn bags it is customary to simultaneously withdraw a plurality of superposed webs of paper from rolls of paper and fold said webs one about the other to form a continuous multiply tube, and often the lateral edges of the multiply tube are folded inwardly between the side walls thereof to form gussets. The tube is then subjected to pressure to crease the fold lines and thus flatten the tube, and the flattened tube is then severed into bag length sections, herein referred to as flat bag tubes. The bag tubes are thereafter transferred to mechanism for completing the construction of the bag. Usually the bag tubes are delivered individually to a sewing machine which closes one or both ends thereof, or first to a machine which tucks, or folds in, one corner of the bag tube to form a valve, and then to the sewing machine.

Heretofore the bag tubes have been delivered manually to the sewing machine or to the valve tucking machine and it is a further object of the invention to provide a mechanism which will automatically withdraw the lowermost bag tube from a stack of such tubes and deliver the same to the proper machine, or other point of discharge.

A further object of the invention is to provide a simple efficient feeding means for advancing the lowermost tube in a stack of tubes with relation to the stack.

A further object of the invention is to provide means for preventing the forward movement of the stack of tubes while permitting the forward movement of the lowermost tube in the stack.

A further object of the invention is to provide means for retaining the forward edge portion of the lowermost tube at, or restoring the same to, a thickness which will permit its movement through a restricted passage.

A further object of the invention is to provide means for completing the withdrawal of a tube which has been advanced by said feeding means and advancing the same to a point of discharge.

A further object of the invention is to provide means for relieving the lowermost tube in a stack

2

of tubes of a portion of the weight of the upper tubes in said stack while it is being withdrawn from said stack.

A further object of the invention is to provide means whereby the several moving parts of the mechanism may be actuated from a single source of power in timed relation one to the other.

Other objects of the invention may appear as the mechanism is described in detail.

10 In the accompanying drawings Fig. 1 is a top plan view of a machine embodying the invention; Fig. 2 is an elevation of the left hand side of the machine, that is, the side which is lowermost in Fig. 1; Fig. 3 is a side elevation of the rear portion of the left hand side of said machine, on an enlarged scale; Fig. 4 is an elevation of the rear portion of the right hand side of the machine, partly broken away; Fig. 5 is a rear elevation of the machine, partly broken away; Fig. 6 is a 15 longitudinal section taken through the machine on the line 6—6 on Fig. 1, showing one series of belts; Fig. 7 is a sectional view taken on the line 7—7 of Fig. 1, partly broken away and with a stack of bag tubes on the supporting structure; and Fig. 8 is a section taken on the line 8—8 of Fig. 3, partly broken away and with a stack of bag tubes on the supporting structure.

In these drawings I have illustrated one embodiment of the invention and have shown the same as designed for feeding flat bag tubes but it is to be understood that the mechanism as a whole, as well as the several parts thereof, may take various forms and may be used for various purposes, without departing from the spirit of the invention.

In the embodiment here illustrated the invention comprises a main frame, or supporting structure, having right and left side members each including upright standards 10, 11 and 12 and longitudinal members 13, 14 and 15, the side members being rigidly connected one with the other in laterally spaced relation by cross bars, such as angle bars 16, 17 and 18. The lower longitudinal members 13 extend rearwardly beyond the upper members 14 and 15 and constitute a support for a stack of bag tubes, as shown in Fig. 7. Preferably this rear portion of the frame is provided with transverse rods 19 and 20 on which are mounted a plurality of laterally spaced longitudinal bars 21 on which the stack of tubes *a* is supported. (Figs. 7 and 8.)

Supported on the frame above the forward portion of the stack supporting part thereof is a device for preventing the forward movement of the stack of tubes while permitting the forward

movement of the lowermost tube with relation to the stack. This device, which is herein referred to as a barrier, is here shown as comprising a plurality of laterally spaced upright bars 22 which are mounted on the upper cross member 16 and a supplemental lower cross bar 23. (Fig. 5.) The lower ends of the laterally spaced bars of the barrier are spaced from the upper surface of the stack supporting part of the frame a distance just slightly greater than the thickness of a single tube, thus forming a passage 24 which permits the forward movement of the lowermost tube in the stack but prevents the simultaneous forward movement of more than one tube. The barrier is vertically adjustable to permit the same to be adjusted to accommodate articles or bag tubes of different thicknesses. As here shown the upright members 22 are secured to the transverse members 16 and 23 by bolt and slot connections, as shown at 25.

A feeding device is provided for individually advancing the lowermost tube of a stack of tubes on the rear portion of said frame. This feeding device may take various forms but preferably it comprises one or more feeding elements 26 mounted for rotation about a common axis below the stack supporting part of the structure (Fig. 7) and adapted upon each rotation thereof to engage and advance the lowermost tube, and move the forward portion thereof through the passage 24. There may be one or more of these feeding elements, depending upon the length of the articles or tubes which are to be fed, and in the present instance there is provided a plurality of feeding elements. In the form here shown each feeding element is in the nature of an arm rigidly mounted on a shaft 27 extending transversely to the main frame and rotatably mounted in the respective side members of the main frame. Each arm has an arcuate outer end surface described about an axis parallel with its axis of rotation and is adapted to move between adjacent bars 21 of the stack supporting part of the structure into engagement with the lowermost tube in the stack of tubes on said bars 21 and move the same forwardly. Preferably the arcuate outer end of the feeding element is provided with a friction surface, as by securing thereto a layer of friction material, such as rubber. The radial length of each feeding element is slightly greater than the distance between its axis of rotation and the lowermost tube in the stack. Thus, as the feeding elements rotate the outer ends thereof will lift a portion of the lowermost tube out of contact with the supporting bars 21 and exerts sufficient force thereon to project the forward end thereof forwardly through and beyond the passage 24. The shaft 27 is provided at one end thereof with a gear 29 (Fig. 2) which meshes with a transmission gear 30 which in turn meshes with a gear 31 secured to the outer end of a short shaft 32 which is connected by bevel gears 33 (Fig. 1) with a power shaft 34, which may be connected at any suitable source of power. Preferably the shaft 34 is connected with the sewing machine, so that the feeding mechanism operates in accurately timed relation to the sewing mechanism.

Mounted between the longitudinal members 13 of the main frame are a plurality of belts 93 extending lengthwise of the frame and supported on pulleys 94 carried by a shaft 95 supported in the side members 13 near the rear ends thereof, and on pulleys 96 mounted on a transverse shaft 97 supported on the frame adjacent to but be-

low the members 13. The shaft 97 and the pulleys 96 are rotated by a gear 98 secured to the shaft and meshing with the transmission gear 30, the rotation being in a direction to move the upper stretches of the belts 93 forwardly. The upper stretches of the belts 93 are arranged adjacent to the respective stack supporting bars 21 and are preferably supported thereon. As here shown (Fig. 8) each bar 21 has an upper portion 21a on which the stack of tubes rests and a lateral portion 21b on which the upper stretch of the belt 93 is supported and on which it moves. The upper surface of the belt may have light contact with the lowermost tube in the stack of tubes but it does not exert material force thereon. In the present arrangement the shaft 95 carrying the pulleys 94 is supported close to the rear end of the main frame but this is not essential and these pulleys may be supported in any suitable position in the rear of the barrier 22. The forward portions of the belts 93 co-operate with and form a part of a second feeding device adapted to engage the forward portion of a tube which has been advanced by the above mentioned feeding device and complete the withdrawal of the same from the sack, and then further advance the same. In the present construction this second feeding device includes a plurality of rollers 99 which are secured to a shaft 100, mounted in the side walls of the main frame, immediately above the upper stretches of the respective belts 93 and in such close relation thereto that a tube moving beneath and beyond the barrier will be gripped between the roller and the belt and moved forwardly thereby. A second series of belts 101 extend about pulleys 102 rigidly mounted on the shaft 100, and about pulleys 103 mounted on a shaft 104 and pulleys 105 mounted on a shaft 106. The lower stretch of each belt 101 is supported in a plane above and parallel with the upper stretch of the corresponding belt 93, and close to that belt. The several pulleys are rotated, as hereinafter described, in a direction to move the lower stretches of the belts 101 in the same direction as the movement of the upper stretches of the belts 93. Thus, a tube moving beneath the barrier will enter the space between the parallel portions of the belts 93 and 101 and will be gripped and moved forwardly thereby, and that movement will continue after the tube is passed beyond the roller 99.

Arranged to receive the tubes from the last mentioned feeding device and move the same toward the point of discharge are a plurality of pairs of belts having superposed portions moving in the same direction. The lower belts 107 extend about pulleys 108 on the shaft 97 and about pulleys 109 on a shaft 110. The upper of the superposed belts, 111, extend about pulleys 112 on the shaft 104, and about pulleys 113 on a shaft 114, with the lower stretches above and close to the upper stretches of the respective belts 107. The shaft 110 is driven from the shaft 97 by the belts 107 and is provided at one end with a gear 115 meshing with a gear 116 on a shaft 114, thus driving the two belts 107 and 111 at opposite directions with their adjacent stretches moving in the same direction. Additional pulleys 117 on the shaft 110 are connected by belts 118 with pulleys 119 on a shaft 120 mounted in brackets 121 on the forward ends of the upper frame members 15, and these belts receive the tubes from the belts 107 and 111 and continue their movement in a substantially horizontal plane. Mounted on a shaft 122 supported on the main

frame above the shaft 120 are a plurality of segments 123 which are rotated in a clock-wise direction, as viewed in Fig. 2, to engage a tube supported on the upper stretch of the belt 118, adjacent pulley 119, and discharge the same from the feeding mechanism or to a position in which it can be engaged by a part of the feeding mechanism of the valve tucking machine. The shaft 122 is driven by a sprocket chain 124 from a shaft 125 having thereon a gear 126 which meshes with the gear 98 on a shaft 97. In the present arrangement the forward edge of the tube engages trip fingers 128 on a rock shaft 129. These fingers accurately position the tubes for delivery to the valve tucking machine and the rock shaft 129 is operated at predetermined intervals to move the fingers out of the path of the tubes and release the same for movement by the segments. As here shown the rock shaft is provided with a crank arm 130 which is connected by a rod 131 with a lever 132 which is actuated by a cam 133 on a shaft 133a. The shaft is driven from the shaft 122 by a chain and sprocket wheel connection 134.

To facilitate the movement of the lowermost tube in a stack of tubes with relation to the stack there is provided means for relieving the lowermost tube of a portion of the weight of the upper tubes. For this purpose there is mounted on the main frame forwardly beyond the barrier a lifting element which is movable into engagement with the forward edge portion of an intermediate tube in the stack of tubes and then upwardly to lift the forward portions of said intermediate tube and of the tubes above the same. As shown in Fig. 7, this lifting element comprises an arm 35 having at its lower end a rearwardly extending part, such as a prong 36, rigidly mounted at its upper end and a shaft 37 extending transversely to the main frame and rotatably mounted in slide blocks 38 which are movable in vertical guide ways 39 in plates 40 at the respective sides of the main frame. Rigidly connected with the shaft 37 and extending downwardly therefrom is an arm 41 adapted to be engaged by a cam 42 on a shaft 43 and moved rearwardly thereby to cause the prong on the arm 35 to engage the aforesaid intermediate tube in the stack of tubes. A second arm 44 is pivotally mounted at 45 on each plate 40 and is connected at its rear end with the corresponding slide block 38. Each arm 44 has at its forward end a roller 46 adapted to be engaged by a cam 47 mounted on a shaft 48 and move the arm 44 in a direction to move the lifting element 36 upwardly and thereby lift the forward edges of a portion of the upper tubes in a stack of tubes out of engagement with the lower portion of the stack. A spring 49 acts on the slide block 38 to move the same downwardly when the cam 47 releases the arm 44. Any suitable number of lifting arms may be mounted on the shaft 37.

Lifting elements may also be provided at the respective sides of the stack of tubes to lift the adjacent edge portions of a part of the tubes and thus further relieve the lowermost tube of the weight of the stack. As best shown in Figs. 3 and 8, there is mounted on the frame at each side of the rear portion thereof an upright structure, here shown as comprising three upright members 50 spaced laterally one from the other lengthwise of the frame. These structures serve both to limit the movement of the tubes transversely to the frame and to support lifting devices and are preferably relatively adjustable transversely to

the frame to accommodate them to tubes of different lengths. As here shown the upright members of each structure are rigidly mounted at their lower ends on the upper member of a two-part clamping device comprising upper and lower members, 51 and 50, having opposed recesses to embrace respectively the upper and lower surfaces of the rods 19 and 20. The upper and lower members of the two clamping devices are connected one to the other by bolts 51 and thus may be adjusted lengthwise of the rods and rigidly secured thereto in adjusted positions thereon. Supporting members or plates 51, 51a and 51b are rigidly secured to and extend outwardly from the respective upright members 50. Mounted in the plates are three shafts, 52, 53 and 54. Mounted on the shaft 52 is a lifting element 55 having at its lower end a prong 56 to engage an intermediate tube in a stack of tubes. Also mounted on the shaft 52 is a second lifting element 57 having at its lower end an inwardly facing block 58, preferably of friction material such as rubber. The lifting element 57 is of such length that the block will engage the edge portions of a plurality of tubes above but adjacent to the lowermost tube and will lift the end portions of the engaged tubes and will also resist the forward movement thereof. The shaft 52 is rotatably mounted in slide blocks 59 mounted in vertical guide ways 59a in the respective plates 51 and urged downwardly by springs 59b. Rigidly secured to the shaft 52 is an actuating arm 60 arranged to be engaged by a cam 61 on the shaft 54 and moved in a direction to move the lifting elements 55 and 57 into engagement with the adjacent edges of tubes in said stack of tubes. A torsion spring 60a mounted on the shaft 52 and connected at one end with the shaft and at its other end with the plate 51b returns the shaft to its normal rotative position when it is released by the cam 61. An arm 62 is pivotally mounted between its ends on the plate 51a for movement about an axis parallel with the shaft 52, as shown at 63, and is mounted at one end on the shaft 52, for a slight longitudinal movement thereon, and is provided at its other end with a roller 64 adapted to be engaged by a cam 65 on the shaft 53 and to thereby move the slide block and lifting elements upwardly to cause the same to lift separate portions of the tubes in the stack of tubes. These lifting mechanisms may be driven in any suitable manner but preferably they are driven from the shaft 27 of the feeding device and as here shown (Fig. 4) a shaft 66 is mounted in bearing brackets 67 and is driven by a sprocket chain 68 extending about sprocket wheels rigidly secured to the outer ends of the shaft 66 and the shaft 27. Adjacent each side of the frame a short shaft 69 is mounted in bearing brackets 70 adjacent each end of the shaft 66 and is connected with that shaft by a bevel gearing 71. A sprocket wheel 72 on each shaft 69 is connected by a chain 73 with a sprocket wheel 74 on the shaft 54 of the adjacent lifting device and the shaft 54 is connected with the shaft 53 by a sprocket chain 75 extending about sprocket wheels 76 and 77 on the shafts 54 and 53 respectively.

The lifting devices are, of course, actuated before the feeding device engages the lowermost tube in a stack of tubes and the upward pressure of the feeding device on the lowermost tube has some tendency to move the forward edge of that tube upwardly and further the tubes, particularly tubes of the gusset type, have a tendency to expand. Therefore, there is provided means

to prevent the upward movement or expansion of the forward edge of the lowermost tube and to restore the forward edge to its normal position and thickness as it has moved upwardly, or expanded, and thereby confine the same to a thickness which will permit it to pass through the passage 24. For this purpose I have provided a holding device to engage the upper portion of the forward edge of the lowermost tube. In the construction shown (Figs. 3 and 7) a shaft 77 extending transversely to the frame, beyond the barrier 22, is mounted at its ends in slide blocks 78 supported in vertical guide ways 79 in the plates 49 and urged downwardly by springs 80. Rigidly secured to the shaft are fingers 81, the lower ends of which normally extend to positions adjacent the lower edge of the barrier. An actuating arm 82 is pivotally mounted between its ends on each side plate 49, is connected at one end with the corresponding slide block 78 and is provided at its outer end with a roller 83 arranged to be engaged by a cam 84 on a shaft 85 to move the slide blocks 78 and the shaft 77 upwardly from its normal position. An arm 86 is rigidly secured to the shaft 77 and is actuated by a cam 87 on a shaft 88 to move the finger 81, while in an elevated position, inwardly above the upper surface of the forward edge of the lowermost tube. While in that position both arms are released by the respective cams and the springs 80 move the fingers downwardly to a position close to and usually in light contact with the lowermost tube, the contact serving to compress the tube sufficiently to permit its movement through the passage or to prevent its upward movement or expansion if it is in a normal position.

All movable parts of the apparatus are driven from a single source of power through the shaft 34. The shaft 97, which is geared to the shaft 34, extends across the main frame and is provided on the right hand side of that frame with a sprocket wheel 135 which is connected by a sprocket chain 136 with a sprocket wheel 137 on the shaft 88. (Fig. 4.) A gear 137a on the shaft 88, not shown in Fig. 4, meshes with a gear 138 on the shaft 85 which meshes with a gear 139 on the shaft 43, and a gear 140 rigid with the shaft 43 meshes with the gear 141 on the shaft 49 whereby these shafts and the parts driven thereby are operated in accurately timed relation one to the other. The belts 167 and 111 are also geared to the power shaft 34 and the pulley 163 for the belt 111 rotates that pulley and drives the belt 161, the pulleys 182 and 183 rotating on their respective shafts and the cam shafts are driven through suitable geared connections with the shaft 97.

While I have shown and described one embodiment of my invention it is to be understood that I do not desire to be limited to the details thereof as various modifications may occur to a person skilled in the art.

Having fully described my invention what I claim as new and desire to secure by Letters Patent, is:

1. In an apparatus for individually feeding flat bag tubes, a supporting structure having a horizontal portion adapted to support a stack of said tubes, a feeding device movably supported on said structure to engage the lowermost tube in a stack of tubes on said structure and move the same forwardly with relation to said stack, a plurality of upright elements supported on said structure to limit the forward movement of the tubes in

said stack above said lowermost tube, each of said elements having a slot in the lower portion thereof and being spaced from said horizontal portion of said structure to permit the passage of said lowermost tube only, a shaft extending transversely to said structure forwardly beyond said upright elements, means for supporting said shaft for vertical movement and for rotary movement, said shaft being biased downwardly, fingers secured to said shaft adjacent to the respective upright members and extending downwardly therefrom and into the slots in the respective upright members, cam means for moving said shaft upwardly, for rotating the same to move the ends of the fingers thereon into positions above the forward edge portion of said lowermost tube in said stack of tubes and then releasing the same for downward movement into engagement with said lowermost tube to confine the edge portion of said tube to a thickness not greater than the spaces between said upright members and said horizontal part of said structure, and operating means for actuating said feeding means and said cam means.

2. In an apparatus for individually feeding flat bag tubes, a supporting structure having a part to support a stack of said tubes, a feeding device movably supported on said structure to engage the lowermost tube in a stack of tubes on said part of said structure and move the same forwardly with relation to said stack, means for actuating said feeding means, means for relieving said lowermost tube of a portion of the weight of the tubes in said stack above the same during said movement thereof, including a lifting element movably supported on said structure and having a part to be engaged with the forward edge portion of an intermediate tube in said stack of tubes, other lifting elements supported on said structure and having parts to be engaged respectively with the lateral edge portions of intermediate tubes in said stack of tubes, means for moving said lifting elements into engagement with the respective edge portions of said intermediate tubes and for imparting upward movement thereto to lift portions of said intermediate tubes out of contact with the next lower tubes.

3. In an apparatus for individually feeding flat bag tubes, a supporting structure having a portion adapted to support a stack of said tubes, a feeding device movably supported on said structure to engage the lowermost tube of a stack of tubes on said structure and move the same forwardly with relation to said stack, a barrier to limit the forward movement of the tubes in said stack above said lowermost tube and comprising a plurality of upright elements spaced laterally one from the other, a shaft extending transversely to said structure forwardly beyond said upright elements, means for supporting said shaft for vertical movement and for rotary movement, said shaft being biased downwardly, fingers secured to said shaft and extending downwardly and rearwardly therefrom, means for moving said shaft upwardly and then rotating the same to move the lower ends of said fingers into engagement with the forward edge portions of tubes in said stack of tubes and then releasing the same for downward movement while in engagement with said tubes, a second shaft rotatably supported above the first mentioned shaft for vertical movement and rotary movement with relation to said structure, fingers rigidly secured to said shaft, extending downwardly therefrom and having rearwardly extending parts, means

for rotating said shaft to engage said parts of said fingers with the forward edge portion of an intermediate tube in said stack of tubes and for then moving said shaft upwardly while said parts are in engagement with said intermediate tube.

4. In an apparatus for individually feeding flat bag tubes, a supporting structure having a portion adapted to support a stack of said tubes, a feeding device movably supported on said structure to engage the lowermost tube of a stack of tubes on said structure and move the same forwardly with relation to said stack, a barrier to limit the forward movement of the tubes in said stack above said lowermost tube, bearing members mounted on the respective side portions of said structure for vertical movement, a shaft rotatably mounted in said bearing members, lifting fingers secured to said shaft for movement therewith and having parts to engage the forward edge portion of an intermediate tube in said stack of tubes, cam means for rotating said shaft in a direction to move said parts of said fingers into engagement with said tube, other cam means for moving said shaft and said fingers upwardly, and means for actuating said cam means in timed relation to first engage said lifting fingers with said intermediate tube and to then elevate the same to lift the forward portion of said tube out of contact with the next lower tube.

5. In an apparatus for individually feeding flat bag tubes, a supporting structure having a portion adapted to support a stack of said tubes, a feeding device movably supported on said structure to engage the lowermost tube of a stack of tubes on said structure and move the same forwardly with relation to said stack, a barrier to limit the forward movement of the tubes in said stack above said lowermost tube and comprising a plurality of upright elements spaced laterally one from the other, bearing members mounted on the respective sides of said structure for vertical movement, a shaft rotatably mounted in said bearing members, lifting fingers secured to said shaft for movement therewith and having parts to engage the forward edge portion of an intermediate tube in said stack of tubes, cam means for rotating said shaft in a direction to move said parts of said fingers into engagement with said tube, other cam means for moving said shaft and said fingers upwardly, and means for actuating said cam means in timed relation to first engage said lifting fingers with said intermediate tube and to then elevate the same to lift the forward portion of said tube out of contact with the next lower tube, other bearing members supported on said structure for vertical movement below the first mentioned bearing members, spring means urging the last mentioned bearing members downwardly, a second shaft rotatably mounted in said last mentioned bearing members, fingers secured to said second shaft for movement therewith and having at their lower ends tube engaging parts, cam means for moving said second shaft upwardly, and other cam means for rotating said second shaft when in an elevated position to engage the fingers thereon with the forward edge portions of the lowermost tube in said stack of tubes and to then release said shaft for downward movement by said spring means.

6. In an apparatus for individually feeding flat bag tubes, a supporting structure having a part to support a stack of tubes, a feeding device movably supported on said structure to en-

gage the lowermost tube in a stack of tubes on said part of said structure and move the same forwardly with relation to said stack, means for actuating said feeding device, shafts extending lengthwise of said part of said structure at the respective sides thereof, means for supporting the last mentioned shafts on said structure for both vertical movement and rotary movement, lifting elements rigidly secured to the respective shafts for movement therewith and having parts to engage the adjacent edge portions of tubes in said stack of tubes above the lowermost tube, cam means for rotating said shafts to move said lifting elements into engagement with said tubes, other cam means for imparting vertical movement to said shafts and said lifting elements to lift said edge portions of the tubes which are engaged by said lifting elements out of contact with the next lower tubes and thereby reduce the weight on said lowermost tube while it is being advanced by said feeding device, and means for actuating said cam means in timed relation to said feeding means.

7. In an apparatus for individually feeding flat bag tubes, a supporting structure having a portion adapted to support a stack of said tubes, a feeding device movably supported on said structure to engage the lowermost tube of a stack of tubes on said structure and move the same forwardly with relation to said stack, means for actuating said feeding device, supplemental supporting structures at the respective sides of said stack supporting part of the first mentioned structure, a lifting mechanism mounted on each supplemental structure, each lifting mechanism comprising a shaft mounted on its said supplemental structure for both vertical movement and rotary movement, a lifting finger secured to said shaft for movement therewith and having a part to engage the adjacent edge portion of an intermediate tube in said stack of tubes, cam means mounted on said supplemental structure for imparting rotary movement to said shaft to engage said lifting finger with said intermediate tube, other cam means mounted on said supplemental structure for imparting vertical movement to said shaft, and means for actuating said cam means to impart said movements successively to said shaft.

8. In an apparatus for individually feeding flat bag tubes, a supporting structure having a portion adapted to support a stack of said tubes, a feeding device movably supported on said structure to engage the lowermost tube of a stack of tubes on said structure and move the same forwardly with relation to said stack, a plurality of upright members mounted on said structure at the respective sides of the stack supporting part thereof and spaced one from the other lengthwise of said structure, a lifting mechanism mounted on each group of upright members and comprising a shaft supported thereon for rotary movement and vertical movement, lifting fingers mounted on said shaft and each having at its lower end a part to engage the adjacent edge portions of a tube in a stack of tubes on said stack supporting part of said structure, an arm secured to said shaft, a cam engaging said arm to move said lifting elements in tube engaging direction, a second arm pivotally mounted on one of said upright members and connected at one end with said shaft to impart vertical movement thereto, a cam acting on the other end of the last mentioned arm to actuate the same, and means driven by the

actuating shaft for said feeding mechanism to actuate said cams in timed relation to said feeding mechanism.

9. In an apparatus for individually feeding flat bag tubes, a supporting structure having a part to support a stack of tubes, a feeding device movably supported on said structure to engage the lowermost tube in a stack of tubes on said part of said structure and move said lowermost tube forwardly with relation to said stack, a shaft for actuating said feeding device, a lifting mechanism supported on said structure at each side of said stack supporting part thereof, each of said lifting mechanisms comprising a shaft extending lengthwise of said structure and mounted on said structure for both rotary movement and vertical movement, a lifting element secured to said shaft for movement therewith and having at one end thereof a part to engage the adjacent edge portion of a tube in said stack of tubes above the lowermost tube, cam means for rotating the shaft of said lifting mechanism to move said lifting element into engagement with said tube, other cam means for imparting vertical movement to the shaft of said lifting mechanism and to the lifting element secured thereto to lift the edge portion of the tube which is engaged by said lifting element out of contact with the next lower tube, and a driving connection between the shaft of said feeding device and the shafts of the respective lifting mechanisms.

10. In an apparatus for individually feeding flat bag tubes, a supporting structure having a part to support a stack of tubes, a feeding device movably supported on said structure to engage the lowermost tube in a stack of tubes on said part of said structure and move said lowermost tube forwardly with relation to said stack, a shaft for actuating said feeding device, supplemental supporting structures mounted at the respective sides of the stack supporting structure, each supplemental structure comprising a plurality of upright members spaced one from the other lengthwise of said apparatus, a shaft mounted in said upright structures for both rotary movement and vertical movement, lifting elements secured to said shaft and having parts to engage the adjacent edges of tubes in said stack of tubes above the lowermost tube and to lift said tubes engaged thereby, an arm secured to said shaft for rotating the same, a second arm mounted on a fixed axis on said supplemental structure and connected with said shaft to move the latter upwardly, two cam shafts mounted on said supplemental structure, a cam carried to one of said shafts to actuate the first mentioned arm, a cam carried by the other of said shafts to actuate the last mentioned arm, a supplemental shaft mounted on said stack supporting structure extending transversely thereto, a driving connection between the shaft of said feeding mechanism and said supplemental shaft, and means for connecting said supplemental shaft with the several shafts on both supplemental structures.

11. An article feeding apparatus comprising a supporting structure having a part adapted to support a stack of articles to be individually advanced by said apparatus, a feeding device supported on said structure below said part thereof to engage the lowermost article of the stack and move it forwardly with relation to the other articles in the stack, a barrier supported above the path of movement of the lowermost article to

5 prevent the forward movement of the other articles in the stack, a second feeding device supported on said structure beyond said barrier to engage an article advanced by the first mentioned feeding device and further advance the same, a trip finger in the path of the advancing article to arrest its advance by said second feeding means and accurately position the article for delivery to the next section of the apparatus, means to move said trip finger out of the path of the advancing article, and operating means for actuating said feeding devices and said trip finger moving means in timed relation.

12. An article feeding apparatus comprising a supporting structure having a part adapted to support a stack of articles to be individually advanced by said apparatus, a feeding device supported on said structure below said part to engage the lowermost article in the stack and move it forwardly with relation to the other articles in the stack, a barrier supported above the path of movement of the lowermost article to prevent the forward movement of the other articles in the stack, a second feeding device supported on said structure beyond said barrier to receive an article advanced by the first mentioned feeding device and continue its advance, said second device including a belt the upper stretch of which is adapted to receive the article and carry it forward, a trip finger mounted on a rock shaft for arresting the forward movement of the article on the said belt, cam means for actuating said rock shaft at predetermined intervals to move said trip finger out of the path of the article and release the article for continued advance, and operating means for actuating said feeding devices and said cam in timed relation.

13. In an apparatus for individually feeding collapsed bag tubes, a supporting structure having a part to support a stack of tubes, a feeding device movably supported on said structure to engage the lowermost tube in the stack and move the lowermost tube forwardly with relation to the stack, a lifting mechanism supported on said structure at each side of said stack supporting part, each of said lifting mechanisms comprising a shaft extending lengthwise of said structure and mounted on said structure for both rotary and vertical movement, a first lifting element secured to said shaft for movement therewith and having at one end thereof a part to engage the adjacent end portion of a tube in the stack above the lowermost tube, a second lifting element secured to said shaft for movement therewith and having at its lower end an inwardly facing block, said second lifting element being of a length such that the block will engage end portions of a plurality of tubes above but adjacent the lowermost tube in the stack, cam means for rotating said shaft to move said lifting elements into engagement with the stack, other cam means for imparting vertical movement to said shaft and to the lifting elements secured thereto, whereby to lift the end portion of the tube engaged by said first lifting element out of contact with the next lower tube and to lift the end portions of the tubes engaged by said block.

14. In an apparatus for individually feeding collapsed bag tubes, a supporting structure having a part to support a stack of tubes, a feeding device movably supported on said structure to engage the lowermost tube in the stack and move the same forwardly with relation to the stack, means for actuating said feeding means, means 70 for relieving the lowermost tube of a portion of

the weight of the tubes in the stack, including a lifting element movably supported on said structure and having a part to be engaged with the forward edge portion of an intermediate tube in the stack, other lifting elements supported on said structure and having parts to be engaged respectively with the lateral edge portions of intermediate tubes in the stack, additional lifting elements having parts to be engaged with the lateral edge portions of a plurality of tubes above but adjacent the lowermost tube in the stack, and means for moving said lifting elements into engagement with the respective edge portions of the tubes and for imparting upward movement thereto to lift portions of said intermediate tubes out of contact with the next lower tubes and to lift the edge portions of the tubes adjacent to the lowermost tube and resist the forward movement thereof.

15. In an apparatus for individually feeding bag tubes having gussets along opposite side edges thereof, a supporting structure having a part to support a stack of the said tubes with a gusseted edge forward, a feeding device movably supported on said structure to engage the lowermost tube in the stack, a barrier supported above the tube supporting part of the structure, said barrier being spaced from said tube supporting part a distance to permit the lowermost tube only to pass beneath the barrier, hold down means including a finger supported at the forward side of said barrier, means operable prior to the movement of said lowermost tube to move said hold down finger rearwardly beyond said barrier to a position above the gusseted leading edge of the 35 lowermost tube and then downwardly to com-

press the gusseted portion of the tube to a thickness less than the distance between the lower edge of the barrier and the tube supporting part, said feeding device including a feeding element 5 adapted to engage the lowermost tube rearwardly of the leading gusseted edge thereof and exert upward and forward force on said tube, whereby to cause the leading edge of the said lowermost tube to dip downwardly beneath the barrier and the entire tube to be fed forwardly under the said barrier.

16. The structure claimed in claim 15 wherein said feeding element comprises an arm secured to a shaft rotatably supported on said structure transverse to said structure and below said article supporting part thereof, said arm having a radial length slightly greater than the distance between the axis thereof and the lowermost article in the stack, and means for rotating said shaft to move the outer end portion of said arm into lifting engagement with the lowermost article in the stack.
